UNITED STATES PATENT OFFICE

DELMONT MARR THORNE, OF GALESBURG, ILLINOIS

TOOL

Application filed December 7, 1928. Serial No. 324,390.

This invention has reference to a fence tool, the primary object of the invention being to provide a tool to facilitate the building and repairing of wire fences.

5 An important object of the invention is to provide a tool of this character which may be employed for removing and driving staples that are used in securing fence wires to their supporting posts.

10 A further object of the invention is to provide a tool of this character which may be used as a wire splicer so that the ends of fence wires may be readily and securely spliced.

15 With the foregoing and other objects in view which will appear as the description proceeds, the invention resides in the combination and arrangement of parts and in the details of construction hereinafter described 20 and claimed, it being understood that changes in the precise embodiment of the invention herein disclosed, may be made within the scope of what is claimed, without departing from the spirit of the invention.

25 Referring to the drawing:

Figure 1 is a side elevational view of a tool constructed in accordance with the invention, a portion thereof being shown in section.

Figure 2 is a view illustrating one edge of 30 the tool, a portion thereof being shown in section.

Figure 3 is an end view of the tool, and

Figure 4 is a fragmental elevational view 35 illustrating the wire splicing extremity of the tool.

Referring to the drawing in detail, the device includes a body portion 5 which is in the form of a bar of a length to permit the tool to be readily and easily handled.

40 One end of the tool is reduced as at 6 and extends slightly laterally, the outer end of the reduced portion extending at right angles defining a pointed finger 7 adapted to be forced into a staple for removing a staple 45 from a post. The outer edge of the finger 7

is curved as at 8 so that the tool may rock over the surface in which the staple is positioned, so that the staple may be removed with little effort. The inner edge of the finger 7 is formed with an enlargement 9 50 that acts as a stop to prevent the finger from being moved too far into the staple to cause the staple to bind in such a way as to prevent its ready removal from the finger 7.

An enlargement 10 is formed at the rear 55 of the tool directly opposite the finger 7, whereupon the tool may be struck by a hammer in the hands of the operator to force the pointed extremity of the finger into the staple being removed. One edge of the body portion, or that portion of the body which may be designated the handle, is cut away defining spaced flanges 11. Adjacent to the outer ends of the flanges, are circular openings 12 and slots 13 leading to the circular openings 60 12, one wall of each slot being curved as at 14, the opposite wall thereof being inclined as at 15, so that the device may be guided over the wires being spliced.

65 In the use of the device as a wire splicer, one end of one wire is bent to form a loop, the end of the adjacent wire is then passed through the loop and bent rearwardly, the free end thereof lying between the flanges 11 in a manner or shown by Figure 4. 70

75 It is obvious that with the wire in this position, the body portion or tool may be rotated causing the extended end of the wire to be wrapped around the main portion of the wire in the formation of a loop.

80 From the foregoing it will be obvious that I have provided a tool which is exceptionally handy when repairing or building wire fences, it being obvious that with the use of this tool, staples may be driven or withdrawn 85 from a supporting post, and that the ends of wires to be spliced may be readily and easily secured.

I claim:

90 A tool for splicing wires, comprising an

elongated body portion, wide flanges formed along the longitudinal edges of the body portion and disposed in parallel spaced relation with each other, said flanges having openings disposed adjacent to one end of the body portion, said flanges having cut out portions extending from one of the respective ends thereof and terminating at the openings, and one wall of the respective cut out portions being curved to guide the tool over a wire.

In testimony that I claim the foregoing as my own, I have hereto affixed my signature.

15 DELMONT MARR THORNE.
